UNITED STATES PATENT OFFICE.

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

TYPEWRITING MACHINE.

Application filed March 25, 1919, Serial No. 284,968. Renewed January 11, 1924.

To all whom it may concern:

Be it known that I, MANSFIELD C. CRAWLEY, a citizen of the United States of America, and a resident of Groton, county of 5 Tompkins and State of New York, have invented certain new and useful Improvements in Typewriting Machines, of which the following is a specification.

The main features of this invention have 10 relation to that type of power-driven machine disclosed in my reissued Letters Patent No. 15,640, dated July 3, 1923 (original Patent No. 1,156,061, dated October 12, 1915), and further elaborated in my co- 15 pending application Serial No. 188,770, filed August 29, 1917, and renewed December 3, 1921, Serial No. 519,804, in which machine a spring-actuated actuator is employed for actuating the type-bars and for letter-spac- 20 ing the carriage, a continuously-driven motor being employed for pulling back and cocking the actuator after each working stroke thereof, the actuator being held cocked until again released by an operation 25 of one of the character-keys or the space-key.

The present invention has for its prin- 30 cipal objects to provide an efficient power- driven force-feed letter-spacing means for the platen carriage of a typewriting ma- 35 chine whereby the carriage may be letter- spaced either toward the right or toward the left; to provide means for insuring accurate letter-spacing and for holding the carriage normally locked against move- 40 ment transversely of the machine; to pro- vide a power-operated letter-spacing mech- anism for machines of the type shown in said patent and application wherein the 45 spring motor which impels the type-bar to printing position is entirely relieved of the work of letter-spacing the carriage, such work being performed wholly by the motor which restores the type-bar actuator to nor- 50 mal position; to provide a power feed mech- anism embodying two feed devices both op- erated by the type-bar actuator and each 55 adapted to feed the carriage in a different direction a full letter space and operating on the same stroke of the actuator to feed the carriage, and means whereby one or the other of said devices may be held out of action during operations of the actuator; to provide means for releasing the carriage from its locking means; and to provide

means whereby a part of the mechanism for letter-spacing the carriage may be em- 60 ployed for driving the carriage continu- ously either to the left or to the right, as more fully hereinafter set forth.

The invention has other objects in view which will appear in the course of this specification.

In the drawings—

Fig. 1 is a view partly in side elevation 65 and partly in vertical section of so much of a typewriting-machine as is deemed necessary to show this invention applied;

Fig. 2 is a perspective view showing the 70 clutch-shifting levers;

Fig. 3 is a front elevation of the carriage- 75 driving gearing and clutch-shifting levers;

Figs. 4 and 5 are vertical sectional views 75 showing the carriage-rack lock device in its two positions;

Fig. 6 is a detail view in bottom plan 80 showing the devices adjusted for forward letter-spacing;

Fig. 7 shows the letter-spacing devices in top plan view and adjusted for forward 85 letter-spacing;

Fig. 8 is a front view, enlarged, of the letter-spacing mechanism;

Fig. 9 is a view of a detail hereinafter 85 described;

Figs. 10 and 11 are plan views showing 90 various portions of the letter-spacing mech- anism and the actuating and controlling means connected thereto;

Figs. 12, 13 and 14 are views of details 95 hereinafter described.

Referring to the various parts by nu- 100 mers, 1 designates the frame of the type- writing machine which, of course, may be of any suitable construction. In the upper 95 part of the frame is the usual platen 2 which is mounted in any suitable way upon the platen-carriage 3. The type-bars 4 are mounted on a suitably constructed type- segment 5 and are adapted to swing up- 105 wardly and rearwardly to the platen. At the rear of the machine is mounted a suit- able continuously-driven motor (not shown) whose drive-pulley 8 is belted or geared to continuously rotate a transverse horizontal 110 shaft 7, the connection between the motor-pulley and this shaft 7 being by a belt or otherwise.

Mounted in the frame, a suitable distance to the rear of the type-bar segment 5, is a 110

coupler-support 11 which is in the form of a segment corresponding approximately to the type-bar segment 5. Pivotally connected to the lower end of each type-bar is a 5 coupler 12 which extends rearwardly and is provided at its rear end with a downwardly-extending foot 13, the lower end of which is formed with a downwardly-and-forwardly-extending locking-toe 14 adapted 10 to rest on the coupler-support 11 and to engage the flange 15 thereon to lock the type-bar against rebound from its rest. To each coupler, near its forward end, is connected a spring 19 which at its lower end is 15 connected to a depending flange on the coupler-rest 11.

Extending rearwardly from the type-bar segment 5 are two horizontal frame-bars 20 which are connected at their forward and 20 rear ends by rock-shafts 21 and 22.

Depending from the shafts 21 and 22, between the frame-bars, are arms 24 and 25, said arms 24 being connected to the shaft 21 and the arms 25 being connected to said 25 shaft 22. The lower ends of each pair of arms 24 and 25 are connected together by a link 26, said links being attached to the segmental type-bar actuator 27, so that said actuator may be swung forwardly and 30 rearwardly and be supported by the arms 24 and 25 and links 26. The links 26 virtually form a part of the actuator and are desirably formed integral therewith. Coiled about the shaft 22, between the depending 35 arms 25, is a spring 23, the free ends of this spring engaging the arms and tending to force them forwardly.

Mounted in the frame-bars 20 is another horizontal rock-shaft 28 which carries two 40 depending arms 29, to the lower ends of which is rigidly secured a segmental universal trip-bar 30 which in its normal position lies close to the heels of the coupler 12, as shown in Fig. 1. Rigidly secured to 45 the drive-shaft 7 is a ratchet-wheel 31. A stub-shaft 32 is in axial alinement with shaft 7 and on one end thereof, adjacent the ratchet-wheel, is mounted an arm 33 which carries a pawl 34, said pawl being pressed toward the ratchet-wheel by means of a 50 suitable coil-spring 34' secured to said arm 33. The arm 33 is provided with a radially-extending stop-lug 36 which is adapted to engage the spring-pressed latch 37, said 55 latch being mounted upon the rear wall of the machine-frame and being pressed into the path of the stop lug 36 by a coil or other spring 37'. Rigidly supported cam 39 is adapted to be engaged by the rear end of 60 the pawl and release said pawl from the ratchet-wheel. Connected to the spring-pressed latch 37 is a forwardly-extending link 40, the forward end of said link being connected to the trip-bar 30. Pivotally connected at its rear end to a crank 41 carried

by the stub-shaft 32 is a link 42 whose forward end is pivotally connected at 42^a to the aforesaid actuator-bar 27.

The couplers 12 are adapted to be selected and raised by the key-levers in the manner set forth in my former patent. When the couplers are raised, the trip-bar 30 is swung rearwardly and the latch 37 is disconnected from the nose 36, thus freeing the type-bar actuator and permitting it to swing quickly 70 forward under the action of its spring 23. After the actuator has performed the work of moving the type-bar to printing position, the cam 39 allows the pawl 34 to engage the ratchet-wheel 32 and thus retract 75 the actuator in the manner set forth in said patent, the latch 37 being again brought into requisition to lock the actuator in its retracted position. Carriage-drive shaft 44 is journaled in the frame-bar 44^a and carries at its upper end a pinion 45 which meshes with the carriage-rack 46, said rack extending transversely of the carriage in the usual way and being secured thereto in any suitable manner. Affixed to this shaft 90 is a short sleeve 47 which carries at its lower end a star detent-wheel 50, and below this detent-wheel is a bevel-pinion 49 which is affixed to the extreme lower end of shaft 44. The detent wheel is adapted to be frictionally engaged by a roller 51 mounted on an arm 52 pivoted at 53 to a suitable part of the frame, said arm 52 being in the form of a bell-crank whose other arm is loosely engaged by the upper end of a lever 54 100 pivotally mounted at 55 to the frame of the machine, the depending end of this lever 54 being provided along its inner edge with differently-inclined faces 56 and 57, for the purpose hereinafter set forth, a spring 58 105 being connected to said lever 54 to hold the lever in normal position and the detent-roller 51 in frictional engagement with the detent-wheel 50.

Pivotally mounted on the vertical shaft 110 44 is a pair of arms 59, these arms resting on the upper end of the short sleeve 47 and being arranged to project radially outwardly in approximately opposite directions. Pivotally attached to the outer end of each 115 of these arms 59 is a link 60 and these two links are converged forwardly into overlapping position and pivotally connected at 61 (by a vertical pivot) to a part of the type-bar actuator 27. These links 60 are 120 not connected directly to the actuator, but are connected indirectly through the medium of a lost-motion cushioning device consisting of a link 62 which at one end supports the aforesaid pivot 61 and at its other end is pivotally connected at 63 to a rearwardly-extending lug 64 carried by the actuator. A coiled spring 65 tends to 125 press the link 62 rearwardly and the free end of the link 62 is supported upon a lug 130

66 projecting rearwardly from the actuator and provided with an upstanding limit-stop 67. With this construction, it will be observed that each time the actuator makes 5 its forward, working stroke, the links 60 will be pulled forwardly and the arms 59 will have their outer ends swung forwardly; and when the actuator 27 is retracted by the motor the links 60 will be pushed 10 rearwardly, the lost-motion device 62—65 serving to cushion the shock that would otherwise be caused by the sudden backward movement of the actuator against the links 60.

15 The rearward movement of the actuator and its connected links 60 is translated into a rotary motion of the carriage-feed shaft 44 by means of either one of a pair of hooked pawls 68, one of which is pivotally connected to each one of the levers 59, a double spring 69 being coiled around the short hub 47 and arranged to normally swing the free hooked end of the pawls toward the detent-wheel 50. These pawls 68 are reversed with 20 respect to each other, so that if they worked together they would work in opposition to each other. Means is provided, however, whereby one or the other of these pawls is held out of action, according to which direction it is desired to feed the carriage. Any suitable devices may be employed for holding one or the other of these pawls 68 out of action; I have shown a cam-plate or 25 shield 80 journaled on shaft 44 and rotatably supported on the star-wheel, said shield being provided with a pair of notches or depressions 81 spaced apart on its edge, these notches being so positioned that in one position the right-hand pawl will be locked out of action and caused to make an idle stroke with its hooked tooth-engaging end working on the rounded periphery of the guard-plate 80, while the other pawl will be permitted by the adjacent notch 81 to 30 engage into a tooth of the detent-wheel upon the backward stroke of the actuator. In this way, either pawl may be held out of commission, altho at all times both pawls will be bodily moved in unison with the actuator. In letter-spacing in the normal direction, i. e., toward the left, the left-hand pawl shown in Fig. 10 will be in action, so that with each return, i. e., idle, stroke of the actuator the carriage will be letter-spaced one step to the left; whereas, if the guard-plate 80 be partially rotated to bring the other notch 81 into the field of action of the other pawl, the carriage will be letter-spaced backwardly (i. e., to the right). 35 It will thus be seen that this letter-spacing mechanism is capable of being readily converted into either a forward letter-spacing mechanism or a rearward letter-spacing mechanism, at the will of the operator. Any suitable means may be employed for shift-

ing the guard-plate 80, but I prefer to shift this device by means of the key-lever 82 whose key will be desirably arranged in the usual keyboard and whose rear end is connected by a vertical link 83 to the guard-plate 80 through the medium of a bell-crank 84 and link 85, so that by merely depressing the key-lever 82 the guard 80 will be rotated on the shaft 44 as a center far enough to reverse the action of the pawl. As this 40 back-spacing adjustment will be called into requisition but infrequently, it is desirable that a spring 85^a be employed to normally hold the guard-plate and its connected parts in position for normal letter-spacing, a stop 85^b being employed to limit the action of the spring. Another feature of importance lies in the fact that in both forward spacing and backward spacing, the work of moving the carriage and its driving mechanism is entirely upon the motor, since it is on the return, non-working, stroke of the actuator that the letter-spacing of the carriage is accomplished, so that the forward, working, stroke of the actuator is entirely relieved of the work of moving the carriage, this being desirable in that it relieves the actuating spring 23 of the actuator of this work of moving the carriage, thereby rendering the use of a lighter spring possible and also contributing to uniformity of blows upon the type-bars. 45

A space-key 70 is provided with an upstanding rod 71 which is held in engagement with the trip-lever 72 whose forward end rests upon the coupler-rest 11 in position to engage the release-segment 30 when said trip-lever 72 is raised by the bar 71 and thus release the type-bar actuator in the manner heretofore described, to enable the carriage to be letter-spaced in either direction without a printing operation. This trip-lever 72 is pivotally supported on the depending arm of a bell-crank 75 whose forwardly-extending arm carries a roller 74 which bears down upon the rounded surface of a stationary member 70 carried by the frame, this roller 74 being held normally against this rounded surface and the trip-lever 72 being normally held against the coupler-support 11 by means of a retractile spring 76. The object of the friction roller 74 and rounded obstruction 77 is to slightly retard the return of the trip-lever 72 to operative position when pulled forward by the type-bar actuator 27. If it were not for this retarding device as applied to the trip-lever 72, the work of returning this trip-lever to normal position would be much lighter than the blow required to actuate the type-bar and, therefore, the blow against the trip-lever would tend to dislocate or unduly wear it and its parts; with this retarding device, however, the work of returning the trip-lever is made approximately equal to the 50

work of actuating one of the type-bars, so that undue vibration and wear are avoided.

I have also provided a mechanism whereby the letter-spacing pinion and shaft are utilized for driving the carriage by a continuous movement either toward the right or toward the left, as occasion may require, this mechanism being particularly useful in that it may be employed for quickly returning the carriage to starting point by means of the motor, thus relieving the operator of the work of returning the carriage at the end of each line.

For this purpose, I arrange a pair of bevel-gears 86 loosely mounted on the aforesaid shaft 7 in such position as to constantly mesh with the aforesaid pinion 49, a double clutch member 87 being arranged between the pinions to lock either one of them to said shaft 7, it being remembered that this shaft 7 is kept in continuous rotation while the machine is in use. A clutch-shifting lever 88 is arranged vertically between the gears 86 for the purpose of shifting the clutch to drive the carriage either toward the right or toward the left, according to which gear 86 is clutched to the shaft 7. This clutch-lever 88 is pivoted at 89 to a stationary part of the machine. To swing this clutch over to the right or to the left, I extend lever 88 downwardly beyond its pivot 89 and provide the same with a pair of opposite cam surfaces or edges 91, a pair of levers 92 each pivoted at 93 being arranged to impinge against these cam edges 91 to swing the lever 88 in either direction according to which of the levers 92 is operated, each of the levers 92 being provided with a lateral finger 92^a for engagement with its adjacent cam surface 91. When the outer end of either lever 92 is swung upwardly by a key-lever 94, the lug 92^a carried thereby is moved downwardly against the adjacent cam surface 91 and in an obvious manner cams the lower end of the lever 88 to the right or to the left according to which lever 92 is operated. With this simple arrangement, it will be observed that the operator may readily bring about a continuous running movement of the carriage in either direction, the key-lever 94 being held manually depressed during this running movement. The carriage may be stopped at the desired point by an ordinary carriage-stop or a tabulator-stop in the well-known manner, and, should the operator continue to press upon the key-lever 94 after the carriage has come to rest against the stop, the clutch being a frictional one will slip sufficiently to prevent injury or strain to the parts.

When the carriage is thus run continuously in either direction, it is, of course, desirable that detent 51 shall be disengaged from the star-wheel, so as to free the motor of the work of moving the carriage against

the friction of said detent, and I therefore provide means for swinging the lever 52 carrying the detent 51 laterally when the clutch is brought into operation. To accomplish this, I extend lever 54 downwardly into the path of the levers 92, the extreme end of the right-hand lever 92 being provided with an additional tappet 92^b to engage against the inclined or cam surface 56 of said lever 54, while the left-hand one of the levers 92 is so arranged that its tappet 92^a engages the other cam surface 57 of the lever 54. In this way, the operation of either lever 92 will cause the lower end of the lever 54 to be shifted laterally to swing the lever into release position and the lever will be held in that position during the movement of the carriage. Additionally, one of the levers 92 may be arranged so as to operate another lever 95 which may be connected by a link 96 with a line-spacing mechanism such as shown in my copending application Serial No. 188,772, filed August 29, 1917, and renewed October 2, 1922, Serial No. 591,989.

To lock the carriage at each step and to prevent it moving more than one step as well as to secure uniform letter-spacing, I provide a quick-acting device for engagement with the rack, such as is substantially disclosed in my co-pending application Serial No. 188,770 hereinbefore referred to. This device consists essentially of a pair of U-shaped members 98 and 99 pivotally connected at their overlapping ends to a bracket 100 attached to the frame-part 44^a at a point alongside of the carriage-driving shaft 44. The upper member 99 is provided with an upstanding finger 101 which is adapted to enter between any two teeth of the carriage-rack and thus lock the carriage, and the lower member 98 is provided with a depending pin 102 which engages in a notch 102^x in the extended end of one of the levers 59. The two members 98 and 99 are connected by a coil-spring 103 so arranged that when the lower member 98 is swung rearwardly by the arm 59 the upper member 99 will be swung rearwardly to take its finger 101 out of the rack, and when the lower member 98 is swung forwardly by said arm 59 the finger will be thrown forwardly into locking engagement with the rack. The spring is so arranged as to ensure quick action of the members 98 and 99, the connection between the pin 102 and the notch in the arm 59 being sufficiently loose to provide for the necessary lost-motion to permit this quick action. My present construction differs from the construction shown in my co-pending application Serial No. 188,770 in that in said other application the rack-locking finger is out of engagement with the rack while the actuator is at rest position because of the fact that the carriage-spacing action takes

place in that structure on the working (forward) stroke of the actuator; while in the present application, by reason of the fact that the carriage is actuated on the return 5 (non-working) stroke of the actuator, I am enabled to move the lock-finger into the rack after each type actuation and keep it in such locked engagement until the next feeding operation.

10 In order to throw out lock-finger 101 from the carriage-rack whenever the carriage is driven forwardly or backwardly by means of the clutch-controlled gearing, I extend the upper end of the lever 54 upwardly into a 15 notch 104^x formed in a sliding bar 104, which bar is provided at its inner end with a cam or beveled edge 105 which is adapted to engage over and force downwardly a lug or ear 106 projecting rearwardly from the upper end of the upper member 99 of the carriage-locking device, whereby the carriage-locking finger 101 will be withdrawn from the rack and held away therefrom simultaneously with the disengagement from the 20 detent 51. As it is sometimes desirable to unlock the carriage-rack as well as the star-wheel without bringing into action the clutch-controlled driving mechanism, I provide the sliding bar 104 with an extension 25 107 which is provided with a thumb-piece 108 at its outer end. By pressing the thumb-piece 108 inwardly, it will be seen that a complete release of the carriage from the drive-wheel as well as the locking-device 30 35 will be effected.

It will be observed that when the lock-finger 101 is in engagement with the rack, it will be held normally in engagement by reason of the fact that spring 103 has been 40 carried bodily forward to a point in front of the pivotal point of the two members 98 and 99, and the spring will also hold pin 102 against the forward wall of the notch 102^x. The parts remain in this position while the 45 machine is at rest. When the actuator moves on its working stroke, the lock-finger will remain in the rack until the spring 103 is carried bodily rearwardly beyond the center of rotation of the two members 98—99, this 50 point being reached very nearly simultaneously with the completion of the forward stroke of the actuator, whereupon (the spring 103 having been moved backwardly beyond center) said spring will, by reason 55 of its retractile tendency, quickly snap the finger out of the rack, thus also throwing the pin 102 rearwardly against the rear wall of the notch 102^x. The parts will remain in this position during the feeding of the carriage, and near the end of the return stroke 60 of the actuator (after the carriage has been fed either backwardly or forwardly) the spring 103 is again carried forwardly beyond center and thus again snaps the finger 65 101 into the rack, thus ensuring the feeding

of the carriage but a single space. It will be observed that it is within the spirit of my invention to arrange the lock-finger so as to engage in the pinion-teeth instead of the rack-teeth, altho it is desirable that the finger shall engage the rack directly so that any lost-motion or looseness that may exist between the pinion and the rack is not permitted to interfere with the accurate spacing of the rack.

In view of the fact that whenever the key-lever 82 is operated to reverse the carriage-feed from a forward to a backward feeding adjustment, it is desirable that a spacing feed shall take place, I provide simple means whereby when said key-lever 82 is operated there shall take place, immediately upon the completion of the reversal adjustment of the pawl-guard or shield 80, a feeding operation. This is done practically by so connecting the 85 said key-lever 82 with the spacing-key-lever-frame 70 that the depression of the key-lever 82 will cause an operation of the spacing-key-lever-frame. To accomplish this, I provide the key-lever 82 with a lateral lug 109 90 (Figs. 11 and 12) extending inwardly from said lever, so as to overhang a projection 110 extending laterally from the key-lever-frame, sufficient lost-motion between the two interlocking parts 109 and 110 being provided in order that the key-lever 82 will have a sufficient preliminary movement to bring about the reversal of the pawl feed as stated before the spacing-lever is depressed far enough to release the actuator.

In order to prevent the carriage-feeding pawls being operated by the accidental operation of a key during the time the carriage is being returned, I provide means whereby the releasing of the type-bar and feed-pawl actuator will be prevented during said movement. To accomplish this in a simple way, I pivotally attach to the carriage-return lever 92 a bar 111 and extend same upwardly and provide its extreme upper end with a lateral lug 112 which overlies the upper edge of the latch-releasing link 40. The link 40 is provided with an up-standing lug 113 which passes back and forth under the aforesaid lug 112 during the 110 normal operation of the machine. When, however, the carriage-return devices are operated, the rod 111 will be pulled down far enough to position the stop 112 behind the link-lug 113 to thus lock the link against 115 rearward movement and thereby prevent the release of the latch 37. The rod 111 may be guided by a pin-and-slot connection 114 on one of the bearings supporting the stub-shaft 32.

The type-bar operating mechanism per se herein shown and described is claimed in my aforesaid reissued patent and in my Patent No. 1,455,112, dated May 15, 1923. The mechanism forming the subject matter 130

of my aforesaid application, Serial No. 188,-
770 (renewal No. 519,804) and of my Pat-
ents No. 1,469,777 and of No. 1,469,778, dated
October 9, 1923, also have certain features
5 in common with the mechanism illustrated
and described in the present application
which are claimed broadly in said patents
and applications.

The nature and scope of the invention
10 having been thus indicated and its pre-
ferred embodiment having been specifically
described, what is claimed as new is:

1. In a typewriting machine, a power-
15 driven type-actuator, a carriage-feeding
mechanism actuated from said type-actuator
and embodying means whereby the direction
of feed of the carriage may be controlled at
will, said means embodying two reversed
20 positively-acting feed-pawls, each arranged
to feed the carriage in a different direction,
and a device for throwing one or the other
into position for action when the feed is
subsequently actuated from the keyboard.

2. In a typewriting machine, motor-
25 operated means for letter-feeding the car-
riage in either direction, and manually-con-
trolled devices for reversing the direction of
feed embodying two reversed pawls and an
adjustable shield for throwing and holding
30 one or the other of the pawls entirely out of
action.

3. In a typewriting machine, devices for
35 actuating the printing instrumentalities, a
letter-space device for the carriage actuated
by said devices, and means manually con-
trolled for reversing the direction of feed
embodying two reversed pawls and a single
40 wheel operable by either pawl.

4. In a typewriting machine, a pinion-
45 and-rack device for letter-spacing the car-
riage in either direction, a toothed-wheel
connected to the shaft of said pinion, a pair
of reversed pawls arranged to cooperate
with said toothed-wheel, means for actuating
50 both pawls at every printing or spacing
operation, and means for bringing either
pawl into operation and putting the other
pawl out of operation, whereby the direc-
tion of feed may be reversed at any point
55 in the travel of the carriage.

5. In a typewriting machine, a motor-
55 actuated reciprocating type-bar actuator, a
carriage-feeding mechanism actuated by the
reciprocations of said actuator, and a car-
riage-locking device actuated to locking
position on the return, non-working, stroke
of said actuator.

6. In a typewriting machine, a spring, a
60 motor, a type-bar-actuating mechanism act-
uated by said spring and retracted by said
motor, a letter-spacing mechanism operated
by said type-bar actuating mechanism to
feed a carriage a full letter-space during
65 each retraction of said actuating mech-
anism by said motor, key-controlled devices

for reversing the direction of letter-feed, and
mechanism for giving the carriage a run-
ning movement in either direction through
the medium of a part of the letter-spacing
mechanism. 70

7. In a typewriting machine, a letter-
spacing mechanism embodying a carriage-
lock and a held detent-wheel to ensure
accurate letter-spacing, a motor-driven
mechanism for returning the carriage
75 through the medium of said feed mechanism,
keyboard devices for putting said mech-
anism into action at will, and devices for
releasing the detent-wheel and also unlock-
ing the carriage when said carriage-return
80 mechanism is put into operation.

8. In a power-driven typewriting ma-
chine, a continuously-rotating shaft, a
traveling carriage, means operated from said
shaft for step-by-step feeding the carriage
85 in either direction embodying a rack and
pinion, and means for continuously driving
the carriage directly from said shaft in
either direction through the aforesaid pinion
and rack, said step-by-step feeding means
90 embodying also a toothed wheel affixed to
the shaft of said pinion, a pair of reversed
pawls adapted to rotate said toothed wheel
in opposite directions, and a rotatable mem-
ber adapted to throw out one or the other of
95 said pawls.

9. In a typewriting machine, a motor-
driven shaft operating continuously, a pair
100 of bevel-gears loosely mounted thereon, a
key-controlled double clutch arrangement
for locking either one of these gears to the
shaft, another shaft carrying a bevel-pinion
being constantly in mesh with both of the
105 aforesaid bevel-gears and also carrying a
pinion adapted to drive the carriage in
either direction, and means for letter-feed-
ing the carriage through the medium of
said pinion and its shaft, said key-controlled
110 double-clutch arrangement embodying a de-
pending lever having a depending free end,
vertically-swinging levers and cam devices
for swinging this depending end in either
direction, and key-levers for actuating these
115 vertically-swinging levers.

10. In a typewriting machine, a letter-
spacing mechanism, a spring-actuated type-
bar-actuator, a motor for retracting this
type-bar-actuator against the action of its
spring, and means whereby when the motor
120 returns the actuator the letter-spacing mech-
anism will be actuated by said actuator to
feed the carriage a full letter-space, thereby
relieving the spring from the duty of letter-
spacing the carriage. 125

11. In a typewriting machine, a motor-
driven type-actuator, a letter-feeding mech-
anism actuated from said actuator and con-
sisting of a pair of pivotal links each carry-
ing a pawl, a star-wheel arranged between
130 said pawls and connected to the carriage

engaging devices, a rotary shield adapted to put one or the other pawl out of commission, and manually-controlled devices for adjusting this shield.

- 5 12. In a typewriting machine, a power-actuated reciprocating type-actuator, a carriage-feeding mechanism actuated by said actuator to feed a carriage only during the return stroke of said actuator, and a carriage-locking device actuated to locking position by said actuator approximately at the end of said return non-working stroke of the actuator. 70
- 10 13. In a typewriting machine, the combination of vibrating power-driven means adapted to cause a type impression when moved in one direction, and force-feed letter spacing mechanism for a paper carriage actuated from said vibrating power-driven means, and arranged to move the carriage only during movements of said vibrating power-driven means in the reverse direction. 80
- 15 14. In a typewriting machine, the combination of type, a paper carriage, two motors, and means whereby one of said motors alone impels the type to printing position and the other motor moves the carriage a full letter space and stores power in the type-impelling motor after each type-impelling operation thereof. 90
- 20 15. In a typewriting machine, the combination of type, a paper carriage, a spring motor, means whereby said spring motor may effect an impression of a selected type on paper on the carriage, a source of power, and means operable from said source of power for storing power in said spring motor and feeding the paper carriage one full letter space after each type impression. 95
- 25 16. In a typewriting machine, the combination of a paper carriage, a reciprocating device for effecting type impressions, a motor for impelling said device in a direction to effect a type impression, a second motor for retracting said device, and means operable to force-feed the paper carriage one full letter space after each type impression by power from said second motor. 105
- 30 17. In a typewriting machine, the combination of a paper carriage, a reciprocating device for effecting type impressions, a motor for impelling said device in a direction to effect a type impression, a second motor for retracting said device, and means operating to force-feed the paper carriage one full letter space after each type impression by power from said second motor exerted during the retraction of said reciprocating device by the second motor. 110
- 35 18. In a typewriting machine, the combination of a paper carriage, a force-feed letter-spacing mechanism for moving the carriage, a reciprocating device adapted to cause type impressions when moved in one direction, power means for operating said 115
- 40 letter-spacing mechanism and said reciprocating device, and means whereby said force-feed letter-spacing mechanism transmits letter-spacing movement to the carriage only during each movement of said device in the reverse direction. 120
- 45 19. In a typewriting machine, the combination of vibrating power-driven means adapted to cause a type impression when moved in one direction, force-feed letter-spacing mechanism for a paper carriage actuated from said vibrating power-driven means and arranged to move the carriage only during movements of said vibrating power-driven means in the reverse direction, and a carriage-locking device actuated from said power-driven means to release the carriage during letter-space movements thereof and lock the carriage after each letter-space movement. 125
- 50 20. In a typewriting machine, the combination of type, a paper carriage, two motors, means whereby one of said motors alone impels the type to printing position and the other motor moves the carriage a full letter space and stores power in the type-impelling motor after each type-impelling operation thereof, a lock for holding the carriage against travel, and means whereby said lock is released by the type impelling motor and moved to locking position by the carriage-moving motor. 130
- 55 21. In a typewriting machine, the combination of type, a paper carriage, a spring motor, means whereby said spring motor may effect an impression of a selected type on paper on the carriage, a source of power, means operable from said source of power for storing power in said spring motor and feeding the paper carriage one full letter space after each type impression, a lock normally preventing travel of the carriage, and means operable from said source of power for releasing said lock during feed movements of the carriage. 135
- 60 22. In a typewriting machine, the combination of a paper carriage, a reciprocating device for effecting type impressions, a motor for impelling said device in a direction to effect a type impression, a second motor for retracting said device, means operable to force-feed the paper carriage one full letter space after each type impression by power from said second motor, a lock operable by said device for normally preventing travel of the carriage, and means whereby said lock is released by movement of said device to effect a type impression and is restored to locking position by retraction of said device. 140
- 65 23. In a typewriting machine, the combination of a paper carriage, a reciprocating letter-spacing device adapted to move the carriage a full letter space, a spring for moving said device in one direction without 145

- moving the carriage, constantly-operating power-driven means for moving said device in the opposite direction to letter-space the carriage and store power in said spring, 5 means for locking said device against movement by said spring, and character-key and space-key operated means for releasing said device.
24. In a typewriting machine, the combination of character and space keys, a paper carriage, and a force-feed letter space mechanism for said carriage embodying a toothed member connected to move the carriage, a forward-spacing pawl arranged to positively shift said toothed member in one direction, a back-spacing pawl arranged to positively shift said member in the opposite direction, power means for moving both pawls upon actuation of either a character 10 key or a space key, and means for rendering either of said pawls ineffective to shift the said member upon actuation of the keys.
25. In a typewriting machine, the combination of character and space keys, a paper carriage, and a force-feed letter space mechanism for said carriage embodying a toothed member connected to move the carriage, a forward-spacing pawl arranged to positively shift said toothed member in one direction, a back-spacing pawl arranged to positively shift said member in the opposite direction, power means for moving both pawls upon actuation of either a character key or a space key, means for rendering either pawl effective at will, and means whereby either of said pawls is automatically rendered ineffective to shift said member when the other pawl is rendered effective to shift said member.
26. In a typewriting machine, the combination of character and space keys, a paper carriage, a force-feed letter-space mechanism for said carriage embodying a toothed member shiftable to move the carriage step-by-step, a forward-spacing pawl arranged to positively shift said toothed member in one direction, a back-spacing pawl arranged to positively shift said member in the opposite direction, power means for moving both pawls upon actuation of either a character key or a space key, and key-operated means shiftable to prevent the forward-spacing pawl from acting on said member and permit the back-spacing pawl to act on said member, said key operated means normally preventing feeding action of the back-spacing pawl and permitting feeding action of the forward spacing pawl.
27. In a typewriting machine, the combination of character and space keys, a paper carriage, a force-feed letter-space mechanism for said carriage embodying a toothed member shiftable to move the carriage step-by-step, a forward-spacing pawl arranged to positively shift said toothed member in one direction, a back-spacing pawl arranged to positively shift said member in the opposite direction, power means for moving both pawls upon actuation of either a character key or a space key, key-operated means shiftable to prevent the forward-spacing pawl from acting on said member and allow the back-spacing pawl to act on said member, said key-operated means normally preventing feeding action of the back-spacing pawl and permitting feeding action of the forward spacing pawl, and means for automatically actuating the space key when said key-operated means is actuated to allow the back-spacing pawl to act on said member.
28. In a typewriting machine, the combination of a reciprocable device for effecting type-impressions, a motor for moving said device in one direction to effect a type-impression, a second motor for retracting said device, a paper carriage, a toothed member shiftable step-by-step to move the carriage for letter-spacing, a forward-spacing pawl for moving said toothed member positively in one direction, a back-spacing pawl for positively moving said member in the opposite direction, means whereby said pawls are shifted by one motor during impression-effecting movements of said device and are shifted by the other motor during retractive movements of said device, and means whereby either pawl may be rendered ineffective to shift said member during reciprocatory movements of said device.
29. In a typewriting machine, the combination of a reciprocable device for effecting type-impressions, a motor for moving said device in one direction to effect a type-impression, a second motor for retracting said device, a paper carriage, a toothed member shiftable step-by-step to move the carriage for letter-spacing, a forward-spacing pawl for moving said toothed member positively in one direction, a back-spacing pawl for positively moving said member in the opposite direction, means whereby said pawls are given a movement by the first motor in one direction and a movement by the second motor in the opposite direction, and means shiftable to render either pawl effective to move said member only during movement of such pawl by said second motor and to simultaneously render the other pawl ineffective to move said member during movement of the latter pawl by either motor.
30. In a typewriting machine, the combination of a reciprocable device, a motor for moving said device in one direction, a second motor for moving said device in the opposite direction, a paper carriage, a toothed member shiftable step-by-step to move the carriage for letter-spacing, two pawls for moving said toothed member positively in opposite directions, means whereby said pawls are reciprocated from said

device, and feed-direction-controlling means for rendering either pawl effective to shift said member and the other pawl ineffective to shift said member, said pawls being arranged to shift said member only during movements of said device in one direction and both pawls receiving their member shifting stroke from the same motor.

31. In a typewriting machine, the combination of a reciprocable device, a motor for moving said device in one direction, a second motor for moving said device in the opposite direction, character keys and a space key, means controlled by said keys for causing said motors to reciprocate said device upon actuation of either of said keys, a paper carriage, a toothed member shiftable to move the carriage for letter spacing, a forward-spacing pawl and a backward-spacing pawl for positively moving said member, means for moving said pawls in one direction by the first motor and in the opposite direction by the second motor, means for controlling the direction of feed shiftable to render either pawl effective to shift said toothed member and simultaneously render the other pawl ineffective to shift said member, means for causing said last-mentioned means to normally throw the back-spacing pawl out of action, a back-space key for temporarily shifting said direction controlling means, and means for actuating the space key from the back-space key.

32. In a typewriting machine, the combination of type, a paper carriage, two motors, character-key-controlled means whereby one of said motors first impels the type to printing position and the other motor then impels the carriage a full letter space and stores power in the type-impelling motor upon actuation of a character key, and key-controlled means for running the carriage continuously in either direction from the motor which letter-spaces the carriage.

33. In a typewriting machine, the combination of a paper carriage, a reciprocating device for effecting type impressions, a motor for impelling said device in a direction to effect a type impression, a second motor for retracting said device, means operable to force-feed the paper carriage one full letter space after each type impression by power from said second motor, and means for running the carriage in either direction with a continuous movement through a part of said force-feed means and solely by power from said second motor.

34. In a typewriting machine, the combination of a paper carriage, a reciprocating device for effecting type impressions, a motor for impelling said device in a direction to effect a type impression, a second motor for retracting said device, means operable to force-feed the paper carriage one

full letter space after each type impression by power from said second motor, means for running the carriage in either direction with a continuous movement through a part of said force-feed means and solely by power from said second motor, a carriage lock operated by said motors to release the carriage during each feed movement and lock the carriage after each feed movement, and means for automatically releasing said lock when said carriage-running means is put into action.

35. In a typewriting machine, the combination of a paper carriage, a reciprocating device for effecting type impressions, a motor for impelling said device in a direction to effect a type impression, a second motor for retracting said device, means operable to force-feed the paper carriage one full letter space after each type impression by power from said second motor, means for running the carriage in either direction with a continuous movement through a part of said force-feed means and solely by power from said second motor, a carriage lock operated by said motors to release the carriage during each feed movement and lock the carriage after each feed movement, means for automatically releasing said lock when said carriage-running means is put into action, and manually operable means for releasing said lock at will.

36. In a typewriting machine, a power-driven carriage-running mechanism embodying a single depending double-clutch shifting lever having cam faces on opposite sides of its depending end, two sub-levers adapted to co-act with said cam faces respectively, and key-levers for actuating said sub-levers.

37. In a typewriting machine, power-driven mechanism for giving the carriage a single running movement in either direction embodying a depending double-clutch shifting lever having opposite cam faces on its depending end, key-actuated sub-levers for engaging said cam faces respectively, and carriage-holding devices for said mechanism actuated to inactive position by either of said sub-levers.

38. In a typewriting machine, power-driven mechanism for running the carriage back and forth embodying a double clutch and a lever for actuating the same, key-actuated sub-levers for swinging said clutch-lever toward one side or the other, a carriage-holding means, and an unlocking lever for actuating said carriage-holding means to inactive position, said unlocking lever having one of its vertical edges provided with two cam faces against which said sub-levers respectively impinge.

This specification signed this 20th day of March, A. D. 1919.

MANSFIELD C. CRAWLEY.
